UNITED STATES PATENT OFFICE.

ALBERT KRAUTH, OF HAMILTON, OHIO.

MUSIC-STAND.

1,271,328.

Specification of Letters Patent.

Patented July 2, 1918.

Application filed May 10, 1916. Serial No. 96,499.

To all whom it may concern:

Be it known that I, ALBERT KRAUTH, a citizen of the United States, and residing at Hamilton, in the county of Butler and State 5 of Ohio, have invented a new and useful Improvement in Music-Stands, of which the following specification is a full disclosure.

My invention relates to folding music racks or stands and refers particularly to 10 improvements upon a device of the character as disclosed in a prior patent issued to me January 25, 1898, numbered 597,722.

Folding racks as made in accordance with 15 said prior patent and as illustrated in Fig. 3 of the drawing hereof, have a center strip provided with a pair of ledge strips at its base or lower portion. These ledge strips at their inner ends are pivoted to the center strip, adapting them to swing from the 20 folded position parallel with the center strip to a position at right angles to the center strip. A brace strip composed of two sections of equal length pivotally united, are pivotally connected at one end to the top 25 of the center strip, with the opposite end pivotally connected with the outer or free end of one of the ledge strips. A pair of rest strips intersecting and pivoted together near the outer ends, respectively, have their 30 inner ends pivoted to separate sections of the brace strip and relatively upon opposite sides of the brace strip. Each rest strip measures equal to the other between the pivot intersectingly connecting the rest strips and 35 the pivot connecting them to a section of the brace strip. Each rest strip correspondingly connects to its brace strip section at the same distance when measured from the axis joining the sections of the brace strip or when 40 measuring from the axis connecting the brace strip to the center strip for one rest strip and the brace strip connection to the ledge strip for the other rest strip.

Such connections of the rest strip to the 45 sections of the brace strip coincide and align one over the other when the rack is folded. This coördination permits the parts to be swung into disarrangement, a form of disarrangement being shown at the right side 50 of Fig. 3. This has the phase of a puzzle difficult for many users to solve, causing inconvenience, and in some instances a return of the rack to the dealer or manufacturer.

An object of my invention is to provide a 55 rack of the type as disclosed in said prior patent, in which such unfolding disarrange-

ment of the parts is impossible and wherein the distance between similar pivot axes of the relative members proportionately is unequal, breaking any coördination in motion 60 of any two members or from moving as a unit about aligned fulcrums.

Other objects and features of the invention will be readily comprehended from the description of the drawings, illustrating a 65 preferred embodiment thereof, and forming a part hereof, and in such drawings like characters of reference denote corresponding parts throughout the several views, of which:—

Figure 1 is a plan view of my improved rack, illustrating the same in unfolded or open position.

Fig. 2 is a view similar to Fig. 1, of a modification.

Fig. 3 is a view of a rack following the construction or rack as shown in the prior patent aforesaid, illustrating the strip from one wing of the rack in a disarranged position.

Referring to Fig. 1 of the drawings, 1 indicates a center strip of the rack, which upon its rear side is provided with the usual socket, not shown, for removably connecting the rack to the shank of a pedestal or stand. 85 A pair of opposite ledge strips 2—2 have their respective inner ends pivotally connected at 3—3 to the lower end or base of the center strip, adapting the ledge strips to lie horizontally in the same plane at right 90 angles to the center strip in an unfolded position of the rack, and fold or swing toward each other parallel with the center strip in a folded position. Each ledge strip at its outer end connects with the center strip 95 through a brace strip comprising two links 4, 5, pivotally united at 6 at a point intermediate between the end extremities of the two as a brace strip with the opposite end of the link 4 pivotally connecting at 7 to the 100 outer end of the ledge strip 2 and the opposite end of the link 5 pivotally connecting at 8 with the center strip at or toward the upper end of said center strip. The connecting ends of said brace strip links move inwardly to the center strip, when folding the rack, bringing the links parallel to each other and to the center and ledge strips with which they connect respectively.

A pair of rest strips 9, 10, are provided 110 intersecting and pivotally united at 11, near their outer ends, and their inner ends are

pivoted to the separate links or sections forming the brace strip, strip 9 connects at 12 to link 4 and strip 10 connects at 13 to link 5, but upon an opposite side from that of strip 9. The various link or strip connections are all made by rivets with their heads countersunk into the parts upon the face side of the rack. The links 4 and 5 are equal in length from their respective axes 10 connecting one with the center piece and the other with the ledge piece to their common or juncture axis, which is necessary to enable the members to move to a parallel position. The strips 9, 10, relatively are of 15 unequal length as between their common axis intersectingly joining the same, and the axis of each connecting the strip respectively to separate links of the brace strip. Thus, the distance between the axis 11 of strip 9 20 and the axis 12, in the construction shown in Fig. 1, is greater than that of its companion strip 10 between its corresponding axes.

Referring to Fig. 1, it will be seen that the distance between the pivot points 13 and 25 6 is greater than that between pivot points 6 and 12 by the same amount that the distance in strip 9 between pivot points 11 and 12 is greater than that on the strip 10 between pivot points 11 and 13.

30 Also, the rest strips' fulcrum connections with the brace strip are relatively located at different distances between the link fulcrums, so that in swinging the parts into their folding parallel position the various 35 axes cannot be brought coaxially or into alinement. This prevents the rest strips, when the rack is folded, from swinging in longitudinal registry about their brace strip axes, or a likewise coördinate motion of the brace 40 strips when their end axes are coaxial, for any movement either to right or left of their axial diametrical alinement, will transmit a link parting or separating motion one to the other at different angular velocity, so 45 that the parts cannot be swung to a disarranged position difficult to correct, and which in the form shown in said prior patent and here illustrated in Fig. 3 was due primarily to the user attempting to unfold 50 the rack by grasping the rest strips and pulling them outwardly away from the center strip, instead of drawing the ledge strip outwardly, which will carry the brace and rest links or strips to a proper unfolded position.

In Fig. 2, the rest strips are shown in an alternate arrangement from that of Fig. 1, as concerns the length between their ful-

crums to break any parallel or unitary motion between two or more of the parts and thereby limit the motion of the parts to and from their folding and unfolding positions.

In Fig. 3 I have illustrated a rack in which the distance between fulcrum points of the various relative or companion members of the combination are equal, with one wing of the rack in a disarranged position, with the rest strip extending in an opposite direction from that which it should normally occupy when the rack is unfolded. 70 To correct it, it offers quite a puzzle to anyone unskilled in solving and in which care must be taken to avoid bending or distorting the parts.

Having described my invention, I claim:—

1. In a device of the class described, a center strip, a ledge-strip having one end pivotally connected to the base of the center strip to move from a position parallel with 80 said center strip to a position at right angles thereto, a brace strip pivoted at one end to the upper portion of the center strip and at its other end to the outer end of the ledge strip, and comprising two members pivotally united, and a pair of rest strips pivotally intersectingly united toward one end, and their opposite ends pivoted each to respective members of the brace strip, said rest strips being of different lengths measured 90 between their common and brace strip axes.

2. In a device of the class described, a center strip, a ledge-strip having one end pivotally connected to the base of the center strip to move from a position parallel with 95 said center strip to a position at right angles thereto, a brace strip pivoted at one end to the upper portion of the center strip and its other end to the outer end of the ledge strip, and comprising two members pivotally 100 united, and a pair of rest strips pivotally intersectingly united toward one end, and their opposite ends pivoted each to respective members of the brace strip, said rest strips being of different lengths measured 105 between their common and brace strip axes, and connected to their brace strip members respectively at points which do not register when the brace strip is folded.

In witness whereof, I hereunto subscribe my name, as attested by the two subscribing witnesses.

ALBERT KRAUTH.
